DESIGN FOR A COMBINED HANDLE AND THUMBPiece FOR A TELEGRAPHIC SEND- ING MACHINE

Horace G. Martin, Brooklyn, N. Y.

Application October 26, 1940, Serial No. 96,103

Term of patent 14 years

To all whom it may concern:

Be it known that I, Horace G. Martin, a citizen of the United States, residing at Brooklyn, in the county of Kings and State of New York, have invented a new, original, and ornamental Design for a Combined Handle and Thumpiece for a Telegraphic Sending Machine, of which the following is a specification, reference being had to the accompanying drawing forming part thereof.

Figure 1 is a top plan view of a combined handle and thumbpiece for a telegraphic sending machine showing my new design;

Figure 2 is a view from one side thereof;
Figure 3 is a view from the front end thereof
and

Figure 4 is a view from the opposite side thereof.

I claim:

The ornamental design for a combined handle and thumbpiece for a telegraphic sending machine, as shown.

HORACE G. MARTIN.
